FREQUENCY RESPONSE CIRCUITS

Robert W. Beckwith, Syracuse, N. Y., assignor to
 General Electric Company, a corporation of
 New York

Application October 10, 1946, Serial No. 702,377

4 Claims. (Cl. 250—27)

1

My invention relates to frequency response circuits and particularly to circuits for the selection of closely-spaced frequencies, such as may be used for example in a frequency-shift communication system.

For the transmission of intelligence, or for telemetering or pilot relaying by carrier-currents, over wire lines, it is often advantageous to use frequency-shift keying in which a carrier wave is shifted back and forth between two different frequencies in accordance with the intelligence or code being transmitted. However, in wide-band systems heretofore employed, difficulty has been experienced due to the effect of interfering "noise" which normally has substantial level in carrier-current systems. Furthermore, in certain power systems, such great use is made of carrier-current over power lines that frequency congestion is a serious problem, and the need is evident for a narrow band frequency-shift system.

I have found in actual practice that a much narrower band width and frequency spacing can be satisfactorily employed for remote telemetering over power lines, with an improvement in signal-to-noise ratio of as high as 25 db. and an increase by as much as twenty times in the number of individual channels that may be placed in a given frequency spectrum, if the frequency selection circuits are given the proper characteristics in accordance with my invention. Specifically, I employ a capacitive bridge network utilizing a piezo-electric element for discriminating between high-frequency signals whose frequencies are relatively close together.

It is accordingly an object of my invention to provide improved frequency response circuits which are particularly adapted for use in a frequency shift system for carrier-current telemetering over power lines.

It is another object of my invention to provide an improved frequency discriminator which is sharply selective, thereby permitting closer frequency spacings between adjacent channels and also providing substantial improvement in reliability under adverse noise conditions or interfering signals.

It is also an object of my invention to provide improved frequency selection circuits, particularly adapted for use in frequency shift transmission system, which give a higher signal-to-noise ratio than heretofore and permit a substantial increase in the number of frequency channels available.

It is still further an object of my invention to provide improved crystal discriminator circuits.

The features of my invention which I believe to

2

be novel are set forth with particularity in the appended claims. My invention itself, however, together with further objects and advantages thereof, may best be understood by reference to the following description taken in connection with the accompanying drawing in which Figs. 1 and 2 are simplified block diagrams of frequency-shift carrier-current transmitting and receiving apparatus, respectively, which illustrate one particularly advantageous use for the circuits of my invention; Fig. 3 is a circuit diagram of a crystal filter particularly adapted for use in the system of Fig. 2; Fig. 4 is a graphical representation illustrating the frequency characteristics of the circuit of Fig. 3; Fig. 5 is a circuit diagram of a crystal discriminator embodying the principles of my invention and which may also be particularly useful in the system of Fig. 2; and Fig. 6 is a graphical representation illustrating the frequency characteristics of the circuits of Fig. 5.

The frequency shift transmitting system shown in Fig. 1 is illustrated as comprising two crystal-controlled oscillators 10 and 11 for generating frequencies f_1 and f_2 used for transmission. These frequencies are alternately supplied through the buffer amplifiers 12 and 13 respectively to the final amplifier 14, the output of which is supplied to the power lines 15 through the usual carrier-current tuning and coupling elements 16.

The shift back and forth between frequencies f_1 and f_2 is accomplished at a coded rate in accordance with intelligence to be transmitted, as is well understood in the art. In Fig. 1 a switch 17 is conventionally represented as being actuated by controlling apparatus (not shown) alternately to energize amplifiers 12 and 13. Of course electronic switching or any other equivalent means for alternately transmitting frequencies f_1 and f_2 at the coded rate may be employed.

It is common practice to transmit a plurality of coded signals simultaneously over the same pair of power lines from a plurality of transmitters, each of which may be similar to that illustrated by the block diagram of Fig. 1. These other transmitters will of course operate at different pairs of frequencies within spaced frequency channels, and their outputs are merely indicated conventionally as being supplied to the power line 15 over other tuning and coupling elements 16a, 16b, etc. The same coupling elements 16 may optionally be utilized for a plurality of channels, because of the close spacing that can be used in accordance with my invention.

In the carrier-current receiving apparatus illustrated in block form in Fig. 2, the pairs of fre-

quencies representative of the codes being transmitted are supplied to the receivers through the tuning and coupling elements 20, 20a, 20b, etc. As in the case of the transmitters, each may optionally be used for a plurality of channels. For reasons that will become more fully apparent later, the frequencies f_1 and f_2 used for each channel are first selected by a crystal filter 21 having a very sharp selectivity characteristic, as indicated by small curve 22, also shown in greater detail in Fig. 4. This filter passes only a relatively narrow band of frequencies including f_1 and f_2 and excludes frequencies outside this band to prevent false operation due to "noise" or unwanted signals from other channels. The selected signals may then be further amplified in amplifiers 23 and 24 and any amplitude modulation present in the signals is then removed in the limiter amplifier 25. These amplifiers may be conventionally coupled together through double-tuned transformers 26 and 27 which will normally have a much broader frequency characteristic than the crystal filter 21, as is indicated by the small curves 28 and 29.

In order to reproduce the transmitted code signal, a very sharply selective, crystal discriminator 30, which will be described in greater detail below, is employed having a frequency characteristic indicated by the small curve 31 in Fig. 2, also shown in greater detail in Fig. 6.

As shown, whenever, the frequency f_1 is received, a positive potential is developed at the output of the discriminator 30, and whenever the frequency f_2 is received a negative voltage is developed. These unidirectional control potentials may then be utilized in any manner known to the art to effect the control or telemetering operation. They are indicated conventionally in Fig. 2 as being supplied to a relay control unit 32 which actuates a relay 33 to energize or deenergize controlled apparatus (not shown).

The arrangement and operation of the crystal filter 21 will be better understood by reference to Figs. 3 and 4 of the drawing. The filter is in the form of a bridge network with the high frequency signals f_1 and f_2 supplied through transformer 40 and resistor 41 to a pair of diagonally opposite input terminals 42 and 43. The output is taken across the opposite diagonal of the bridge, between terminals 44 and 45, one of which may be grounded. The high-frequency currents may flow through either of two parallel paths between the input terminals 42 and 43, as indicated by the instantaneous current vectors i_1 and i_2 . The current i_1 flows through two bridge arms comprising a piezo-electric crystal 46 and a resistor 47 respectively, while the current i_2 flows through the other two bridge arms comprising a variable capacitor 48 and resistor 49 respectively. It will be observed that the high-frequency potentials developed between the output terminals 44 and 45 are the result of the difference between the voltage drops across resistors 47 and 49, these being indicated by the vectors e_1 and e_2 respectively.

The crystal filter of Fig. 3 is adjusted to pass only a narrow frequency band including f_1 and f_2 . As indicated in Fig. 4 the selectivity curve of the crystal filter circuit is extremely sharp. In one frequency shift, carrier-current telemetering system embodying my invention, the frequencies f_1 and f_2 for one controlled channel were 130.00 and 130.105 kc. respectively, and the two frequencies employed for the next adjacent channel were 131.000 and 131.107 kc. respectively. The actual frequency characteristic of the filter used in the

second channel is shown by the curve 22 in Fig. 4. To illustrate the sharpness of this curve, there has been superimposed upon it a theoretical curve 18 for a single-tuned circuit having the extremely high "Q" of 1300. It will be seen that the crystal filter gives the same shape of peak with even better sideband attenuation.

The operation of the crystal filter circuit 21 of Fig. 3 will be better understood when it is realized that the piezo-electric crystal 46 (including its holder) appears as substantially a pure capacitance at frequencies removed from the narrow range in which it exhibits resonance characteristics. Therefore, it is possible to adjust the variable capacitor 48 so as substantially to balance the capacitive current through the crystal for frequencies above and below this range, so that the potentials e_1 and e_2 very nearly cancel each other. If the resistors 47 and 49 are equal, then of course the capacitance of capacitor 48 will be adjusted to be equal to the equivalent capacitance of crystal 46 with its holder. Under these conditions, no output will result at terminals 44 and 45 except in the region where crystal 46 goes through its well-known resonant characteristic. Since this characteristic is very sharply defined, the resulting selectivity curve for the filter is extremely sharp, as previously pointed out. Without the capacitor 48, a much broader selectivity characteristic would be obtained. Looking at it another way, the voltage e_2 is practically constant over the operating frequency range and subtracts from e_1 to bring the side of the selectivity curve towards zero very quickly on either side of the resonance peak, as the bridge approaches a balance.

It will be appreciated by those skilled in the art that the output resistors 47 and 49 in Fig. 3 might be replaced by capacitors or inductances under some conditions. The input circuits through transformer 40 might also be series-resonated or parallel-resonated at the operating frequency to give additional sideband reduction, and in general it will be found that this is desirable since the input impedance can be matched to the source of signal and thus greater receiver sensitivity obtained.

The crystal discriminator 30 shown in Fig. 5, also comprises a four-arm bridge network somewhat similar to that of Fig. 3 but the frequency characteristics thereof are entirely different, as illustrated in Fig. 6. The input signals are supplied through the transformer 50 to the diagonally opposite pair of input terminals 52 and 53 while the output is taken across the terminals 54 and 55, one of which may be grounded as shown. As indicated by the current vectors I_1 and I_2 , currents may flow from terminal 52 to terminal 53 through two parallel paths. The current I_1 flows through the piezo-electric device 56 and a load impedance, indicated as a resistor 57, while the current I_2 flows through the variable capacitor 58 and a load impedance, indicated as a resistor 59. The circuit differs from that of Fig. 3 in that unilateral conducting devices, represented as diode rectifiers 60 and 61, are included in each of the parallel paths. These rectifiers are poled to permit current flow in the same direction, i. e., from terminal 52 toward terminal 53. The resistors 57 and 59 are bypassed for the frequencies of the input signals by capacitors 62 and 63, as is conventional in diode detector circuits. Direct current return paths from the anodes of the detector 60 and 61 to ground are also provided by the resistors 64 and 65 in shunt to the crystal 75 56 and the variable capacitor 58 respectively,

This direct current return could be provided by inductances whose reactances are large compared to the reactance of the capacitor 58.

It is well known in crystal theory that as the frequency applied to a crystal is raised from a frequency below the range in which it exhibits resonance phenomena, it first passes through a point at which it looks like a series-resonant circuit and then through a point at which it looks like a parallel resonant circuit, with the separation between these points quite small. I take advantage of this phenomena, in accordance with my invention, by selecting the frequencies f_1 and f_2 close enough together so that the crystal 56 can be ground to exhibit these resonance characteristics in the vicinity of the two frequencies. As previously described in connection with the circuits of Fig. 3, the crystal looks like a substantially pure capacitance (considering the complete crystal assembly in its holder) for frequencies above and below this range.

With these facts in mind, it will be readily apparent how the crystal discriminator circuits of Fig. 5 are adjusted to produce the frequency characteristics shown in Fig. 6. The value of capacity 58 is adjusted to balance the currents I_1 and I_2 flowing through the two parallel paths for frequencies outside the resonant range of the crystal, just as in the case of Fig. 3. At the lower frequency f_1 , the current I_1 through the crystal exceeds the current I_2 through the capacitor 58 due to the lower impedance of the crystal. Therefore the resultant rectified potential E_1 exceeds the potential E_2 , resulting in a positive potential at terminal 55 with respect to ground. The opposite is true at the higher frequency f_2 , in which case the potential E_1 becomes much smaller than potential E_2 due to the relatively high impedance of the crystal. Over the relatively narrow range of frequencies involved, the potential E_2 is substantially constant.

It will also be appreciated that the frequencies f_1 and f_2 may be selected in some cases to lie closer together than those illustrated, in which case they would fall at points closer to the horizontal axis of Fig. 6 along the sharply-sloped, center portion of the curve. However, I have found that greater frequency stability of the circuits, with greater freedom from the effects of temperature, humidity and other factors, is obtained by selecting these frequencies so as to coincide substantially with the positive and negative peaks of the curve, respectively.

It will be understood that the curves of Figs. 4 and 6 can be applied to other frequencies than those specifically shown if the f_1-f_2 spacing remains approximately a constant percentage of their average frequency. Thus the horizontal scale may be expressed in terms of percent deviation from center frequency in a more generalized expression.

It will now be apparent that I provide simple and effective frequency selection circuits, particularly adapted to the requirements of a frequency-shift, telemetering system, in which the number of available frequency channels may be increased while at the same time providing greater freedom from noise interference and interference due to cross-talk between signaling channels. My circuits are also obviously adaptable to use in a space radio system, at the same or higher frequencies.

While I have shown particular embodiments of my invention and suggested certain modifications that may be made therein, it will, of course,

be understood that I do not wish to be limited thereto since various other modifications will readily occur to those skilled in the art. I therefore contemplate by the appended claims to cover any such modifications as fall within the true spirit and scope of my invention.

What I claim as new and desire to secure by Letters Patent of the United States is:

1. In apparatus for discriminating between waves of two different frequencies, the combination of a pair of input terminals to which said waves are supplied, a pair of parallel current paths between said terminals, each path including a rectifying device and a load impedance adapted to have unidirectional potentials developed thereon in response to said waves, each path also serially including a current controlling element, one element being a piezo-electric crystal exhibiting series resonance and parallel resonance near said two frequencies respectively and substantially pure capacity reactance above and below said frequencies, the other element being a capacity, output means responsive to the difference between potentials developed across said load impedances, said capacity being adjusted to impress minimum resultant output potential on said output means at frequencies for which said crystal exhibits substantially pure capacity reactance.

2. In apparatus for discriminating between waves of different frequencies lying within a relatively narrow frequency band, a pair of input terminals for said waves, two parallel paths between said terminals, each path including a unilaterally conducting element and a load impedance adapted to have unidirectional potentials developed thereon in response to said waves, said elements being poled to permit current flow in the same direction between said terminals, one path further serially including a capacitance and the other path a piezo-electric crystal, said crystal exhibiting a relatively high impedance near one edge of said band and a relatively low impedance near the other edge of said band, means for adjusting said capacitance substantially to balance the currents through both paths at frequencies outside said band, and output means responsive to the difference between unidirectional potentials developed across said load impedances.

3. Apparatus responsive to signals having frequencies lying within a predetermined band comprising, in combination, a four-arm bridge network having a pair of diagonally opposite input terminals to which said signals are supplied, first and second arms adjacent one of said terminals each comprising a resistance in parallel to a capacitance of low impedance at said frequencies, third and fourth arms adjacent said other terminal, said third arm serially comprising a capacity element and said fourth arm serially comprising a piezo-electric element, said piezo-electric element being series-resonant near one edge of said band and parallel-resonant near the other edge of said band, a pair of unilateral conducting devices also serially included in said third and fourth arms respectively and poled to permit current flow in the same direction between said terminals, means providing direct-current paths in shunt to each of said elements, means for adjusting said capacity element substantially to balance the effective capacity of said piezo-electric element outside said band, and output means connected across said first and second arms.

4. In apparatus for discriminating between waves of different frequencies lying within a relatively narrow frequency band, a pair of input ter-

minals for said waves, two parallel paths between said terminals, each path serially including a unilaterally conducting element and a load impedance, each of said impedances being shunted by a capacity of low reactance at said frequencies and adapted to have unidirectional potentials developed thereon in response to said waves, each path further serially including a current-controlling element, one element being a piezo-electric device resonating within said band and having substantially pure capacitance outside said band, the other element being a capacitance having a value substantially to balance the currents in said two paths for said frequencies outside said band, and a utilization circuit responsive to the difference in potentials on said load impedances.
